UNITED STATES PATENT OFFICE.

THOMAS L. LEE, OF ROCHESTER, NEW YORK, ASSIGNOR TO NORTH EAST ELECTRIC COMPANY, OF ROCHESTER, NEW YORK, A CORPORATION OF NEW YORK.

ELECTRIC SWITCH.

Application filed June 8, 1921, Serial No. 478,050. Renewed November 15, 1927.

This invention relates to electric push-switches of the type in which a contact-member in the form of a laminated spring is used.

5 The object of the invention is to produce a switch of simple and inexpensive construction, which shall be reliable in operation, and particularly one in which the parts are insulated in a simple but effective manner.

10 In switches of the type in question it has been customary to use a spring-controlled metal plunger carrying the spring contact-member, and to insulate this contact-member from the metal plunger. It has 15 also been common to prevent rotation of the plunger and the contact-member by the use of stationary insulating material within the switch-casing. In accordance with the present invention the construction is simplified 20 by mounting the contact-member on a plunger of insulating material, and providing this plunger with non-circular projections or keys engaging corresponding grooves in the casing, so that rotation of the plunger 25 is prevented.

Other features of the invention will be set forth more particularly in the following description of the illustrated embodiment of the invention.

30 Figs. 1 and 2 are, respectively, a side-elevation and an end-elevation of a switch embodying the present invention, together with an instrument-board or the like on which switch is mounted, the switch being 35 shown partly in axial section. Fig. 3 is a plan-view of the switch, in section on the line 3-3 in Fig. 1.

The illustrated embodiment of the invention comprises a casing 5 within which two 40 stationary contact-members 6 are mounted and insulated. These contact-members have stems 7 projecting outwardly and constituting binding-posts.

The movable contact-member 8 comprises 45 a set of spring-blades of the usual form. These blades are perforated and are fixed together by means of a metal eyelet 9 and a washer 10 cooperating therewith. The plunger 11 is formed of insulating material, 50 preferably a plastic material, such as bakes-

lite, which can be readily moulded to form. Fixed in the plunger, preferably by moulding it therein, is a metal insert or core 12, by which the movable contact-member is supported and attached to the plunger. For 55 this purpose the core is knurled for part of its length, and the eyelet 9 is pressed tightly upon the knurled portion as shown in Fig. 1, thus being fixed on the core. The lower extremity 13 of the core serves as a 60 guide for the coiled spring 14 by which the plunger is held normally in the raised position, with the contact-members disengaged.

The plunger moves in a bearing or sleeve 15, projecting integrally from the body of 65 the casing 5, and this sleeve is provided with two grooves or keyways, which are engaged by integral projections or keys 16 formed on the plunger. These keys prevent the plunger from rotating, and thus prevent engagement of the movable contact-member 70 with the sides of the casing.

The switch as illustrated is designed to be mounted in the form of a flush switch, on a panel or board 17, being secured in 75 place by screws 18 and an escutcheon-plate 19. As so arranged, the upper or outer end of the plunger 11 has the form of a push-button, as shown.

The bottom of the casing is formed by a 80 removable plate 20, on which the stationary contact-members are mounted, and this plate may be removed whenever necessary to adjust or repair the mechanism of the switch. It should be noted that owing to the close 85 engagement of the core 12, the eyelet 9 and the contact-blades 8, these parts act substantially as a single solid conductor, so that the conductivity of the movable switch-blades is not substantially impaired by perforating them in the manner shown. 90

The invention claimed is:

1. In an electric switch, the combination 95 of a casing provided with a bearing-sleeve; fixed contact-members mounted in the casing; a movable contact-member cooperating with said fixed contact members and comprising a plurality of spring-blades perforated and secured together by a metal eyelet; a metal core fixed in said eyelet; and 100

a plunger of insulating material, in which said core is fixed, said plunger being slideable in said bearing-sleeve in the casing.

2. In an electric switch, the combination of a casing provided with a bearing-sleeve; fixed contact-members mounted in the casing; a movable contact member cooperating with said fixed contact-members and

comprising a plurality of spring-blades 10
perforated and secured together by an eye-
let; a metal core having a friction-fit in said
eyelet; and a plunger, of insulating mate-
rial, molded on said core and slidingly
mounted in said bearing-sleeve in the cas-
ing.

THOMAS L. LEE.
